UNITED STATES PATENT OFFICE.

HENRY GRENON, OF NEW HAVEN, CONNECTICUT.

DESIGN FOR A COLLAR AND CUFF SMOOTHER.

SPECIFICATION forming part of Design No. 31,755, dated October 31, 1899.

Application filed October 5, 1899. Serial No. 732,725. Term of patent 3½ years.

To all whom it may concern:

Be it known that I, HENRY GRENON, a citizen of the United States, residing at New Haven, in the county of New Haven and State of Connecticut, have invented and produced 5 a new and original Design for Collar and Cuff Smoothers, of which the following is a specification, reference being had to the accompanying drawings, forming part thereof, and in 10 which—

Figure 1 is a front elevation showing my design, and Fig. 2 is a side elevation of the same.

As shown in the drawings, my design consists of a conical-shaped article A, the leading 15

or material features of which are the concave grooves a and a' and conical point a^2 .

Having described my invention, what I claim as new, and desire to secure by Letters Patent, is—

The design for a collar and cuff smoother, as herein shown and described.

In witness whereof I have hereunto set my hand, at New Haven, in the county of New Haven, State of Connecticut, this 3d day of 25 October, 1899.

HENRY GRENON.
